SANDING DRUM

Glenn W. Stahl, Warrensburg, Mo.

Application May 14, 1941, Serial No. 393,467

3 Claims. (Cl. 51—194)

This invention relates to sanding drums, and more particularly to the securing of abrasive material thereon, and has for the primary object the provision of a securing device for the purpose specified which will permit easy and quick application of abrasive, in sheet formation, onto the periphery of the drum and which is actuated or caused to grip and retain the abrasive sheet by centrifugal action during the rotation of the drum, obviating the danger of the abrasive sheet accidentally detaching from the drum during the use of the latter and which will permit easy removal of the abrasive sheet from the drum whenever need may occur to substitute another sheet therefor.

With these and other objects in view as will become more apparent as the description proceeds, the invention consists in certain novel features of construction, combination and arrangement of parts which will be hereinafter more fully described and claimed.

For a complete understanding of my invention, reference is to be had to the following description and accompanying drawings, in which

Figure 1 is an end elevation, partly in section, illustrating a sanding drum equipped with a securing means constructed in accordance with my invention.

Figure 2 is a plan view illustrating a drum with a throat or slot in the periphery thereof to permit the engaging of the ends of an abrasive sheet with the securing means.

Figure 3 is a sectional view taken on the line 3—3 of Figure 1.

Figure 4 is a perspective view illustrating the securing device or element.

Figure 5 is a perspective view illustrating one of the end plates of the drum.

Referring in detail to the drawings, the numeral 5 indicates a drum having an axial bore in which is secured a shaft 6 for the rotation of the drum. One end of the drum is covered by a removable plate 7 held in position by fasteners 8. The other end of the drum is covered by a removable plate 9 held in position by fasteners 10 and provided with an opening 11 to permit the shaft 6 to extend therethrough.

Formed in the drum eccentrically of the bore is a chamber 12 to receive a pivotal securing device or element 13. The chamber 12 is so constructed as to provide converging walls 14 and a substantially cylindrical shaped portion 15. The drum 5 is further provided with a throat 16 in the form of a slot formed in the periphery of the drum and extending the full length of the

latter. The throat connects with the chamber 12, as clearly shown in Figure 1.

The securing device 13 is in the form of a plate 17 having opposite converging walls and a substantially cylindrical portion 18. The cylindrical portion 18 is journaled in the cylindrical portion of the chamber 12 and the plate 17 of the securing device has a limited pivotal movement between the converging walls of the chamber.

A rib 19 is formed on one of the converging walls of the plate 17 adjacent the free end of the latter.

The periphery of the drum has a covering 20 constructed of leather, rubber or any other material suitable for the purpose to provide a cushion seat for a sheet of abrasive material 21. The covering has a slot to match the throat 16 so that the ends of the sheet of abrasive material 20 may be inserted into the chamber by way of the throat to permit the ends of the sheet of abrasive material to be confined between one wall of the chamber 12 and one of the faces of the plate 17.

It is preferable that the ends of the sheet of abrasive material have tight fit with the wall of the chamber and with one face of the plate 17 of the securing device. Further, it will be seen that the rib 19 also bears against one of the end portions of the sheet of abrasive material.

When the drum is in operation, it rotates in the direction indicated by the arrow in Figure 1 and due to centrifugal action the securing device 13 is forced in the direction of one of the walls of the chamber 12 forcing the ends of the sheet of abrasive material against said latter-named wall and thereby firmly anchoring the sheet of abrasive material on the periphery of the drum, 40 which with the covering will prevent the sheet of abrasive material from creeping on the drum.

From the foregoing, taken in connection with the accompanying drawings, it will be seen that a very simple securing device has been provided for securing the ends of an abrasive sheet in a chamber provided in a drum so that the abrasive sheet may extend entirely about the periphery of the drum from end to end of the latter and will be prevented from creeping or becoming accidentally detached during the use of the drum. Still the device constructed in accordance with the foregoing will permit the easy removal of the abrasive sheet whenever need may occur without removing separable fasteners and equivalent securing devices.

While I have shown and described the preferred embodiment of my invention, it will be understood that minor changes in construction, combination and arrangement of parts may be made without departing from the spirit and scope of the invention as claimed.

Having thus described the invention, what I claim is:

1. In a device of the character described, a drum having an eccentrically located chamber to its axis of rotation and provided with a throat in the periphery thereof communicating with said chamber, said chamber including converging walls and a cylindrical portion journaled within the cylindrical portion of the chamber, said plate coating with one of the converging walls of the chamber and a cylindrical portion journaled within the cylindrical portion of the chamber, said plate coating with one of the converging walls of the chamber in gripping ends of an abrasive sheet inserted in the chamber by way of the throat by centrifugal action during the rotation of the drum.

2. In a device of the character described, a drum having an eccentrically located chamber to its axis of rotation and provided with a throat in the periphery thereof communicating with said chamber, said chamber including converging walls and a cylindrical portion, a fastening device including a plate having converging walls arranged opposite the converging walls of the chamber and a cylindrical portion journaled within the cylindrical portion of the chamber, said plate coating with one of the converging walls of the chamber in gripping ends of an abrasive sheet inserted in the chamber by way of the throat by centrifugal action during the rotation of the drum.

5 chamber and a cylindrical portion journaled within the cylindrical portion of the chamber, said plate coating with one of the converging walls of the chamber in gripping ends of an abrasive sheet inserted in the chamber by way of the throat by centrifugal action during the rotation of the drum, and a rib formed on the plate adjacent its free end and on one of the converging faces to contact the abrasive sheet.

10 3. In a device of the character described, a drum having an eccentrically located chamber to its axis of rotation and provided with a throat in the periphery thereof communicating with said chamber, said chamber including converging walls and a cylindrical portion, a fastening device including a plate having converging walls arranged opposite the converging walls of the chamber and a cylindrical portion journaled within the cylindrical portion of the chamber, said plate coating with one of the converging walls of the chamber in gripping ends of an abrasive sheet inserted in the chamber by way of the throat by centrifugal action during the rotation of the drum, a rib formed on the plate adjacent its free end and on one of the converging faces to contact the abrasive sheet, and a cover for the periphery of the drum and having its ends spaced at the throat and forming a cushion seat for the abrasive sheet on the periphery of the drum.

GLENN W. STAHL.
